TOOTH FOR EXCAVATING APPARATUS

William W. Wilson, 6204 W. Mountain Ave.,
Shreveport, La.

Filed Mar. 9, 1964, Ser. No. 78,921

Term of patent 14 years

(Cl. D39—1)

FIG. 1 is a perspective view of a tooth for excavating apparatus showing my new design,

FIG. 2 is a rear view thereof,

FIG. 3 is a front view thereof,

FIG. 4 is a side view thereof,

FIG. 5 is a top plan view thereof,

FIG. 6 is a bottom plan view thereof,

FIG. 7 is a sectional view on the line 7—7 of FIG. 1.

I claim:

The ornamental design for a tooth for excavating apparatus, as shown and described.
